UNITED STATES PATENT OFFICE

126,375

DESIGN FOR AN INCINERATOR

Pearl O. Carter, Los Angeles, Calif.

Application August 12, 1940, Serial No. 94,379

Term of patent 3½ years

To all whom it may concern:

Be it known that I, Pearl O. Carter, a citizen of the United States, residing at Los Angeles, in the county of Los Angeles and State of California, have invented a new, original, and ornamental Design for Incinerators, of which the following is a specification, reference being had to the accompanying drawing, forming part thereof.

The figure is a perspective view of an incinerator, showing my new design.

The rear side of the incinerator is substantially like the front as illustrated, with the exception of the drawer front panel shown at the bottom of the body.

I claim:

The ornamental design for an incinerator, as shown and described.

PEARL O. CARTER.
